GRATING ANCHOR

Walter A. Bates, Joliet, Ill., assignor to
Beulah H. Bates, Joliet, Ill.

Application October 19, 1946, Serial No. 704,421

5 Claims. (Cl. 189—84)

1

The present invention relates to improvements in grating anchors.

More particularly, the present invention relates to means for anchoring gratings such, for example, as those used in the floors of industrial plants and the like. Gratings of the kind referred to are commonly formed of a plurality of parallel bars called main bars connected by means of cross bars, the assembly forming a unit adapted to be supported upon side members which may take the form of structural steel shapes of well known contour. The present applicant on March 1, 1946, filed an application entitled "Anchors for Gratings," Serial No. 651,219, which relates to the same general subject matter as the present invention. The present invention has for one of its objects the provision of a grating anchor which includes advantages of the subject matter of the application aforesaid and embodies further advantages.

A further object is to provide an improved grating anchor readily applicable to gratings of known design, which is simple in construction and easy to assemble and disassemble when the grating is located in operative position upon the supporting members therefor.

A further object is to provide a grating anchor well adapted to meet the needs of ordinary service.

Referring to the drawings,

Figure 1 is a view in sectional elevation taken through a grating having applied thereto one embodiment of the present invention;

Figure 2 is a top plan view of the structure shown in Figure 1;

Figure 3 is a sectional view taken along the plane indicated by the arrows 3—3 in Figure 1;

Figure 4 is a perspective view of a clamping member forming part of the structure illustrated in the preceding figures; and

Figure 5 is a fragmentary view similar to a portion of Figure 1 but illustrating a slight modification.

The numerals 10—10 indicate the main bars of a grating. The numerals 11—11 indicate cross bars which extend through apertures in said main bars and hold said main bars securely in spaced parallel relationship. The top edges of said main bars 10—10 ordinarily lie in a single plane and the bottom edges of said main bars lie in another plane. The numeral 12 indicates an angle member presenting a horizontal flange 12a for the reception of ends of the main bars 10—10.

An anchor for holding the grating in position on the angle member 12 is indicated as a whole by the numeral 13. Said anchor comprises the following parts: The holding member 14, the bolt 15 and the clamping member or clamp 16.

2

The holding member 14 may be made of sheet metal which may be stamped out of a flat sheet and swaged into the shape illustrated in Figures 1, 2 and 3. Said holding member 14 includes the elongated leg portion 17, the bent over portion 18 and the shorter leg portion 19 provided with the flange 20 having an aperture therein (not illustrated). The legs 17 and 19 are spaced apart a distance slightly greater than the thickness of a main bar 10. The clamp 16 is a member, preferably of metal, bent upon itself to form a leg 21 which at the bend 23 is connected with the leg 24. The leg 24 is wedged out of alignment with the leg 21 in a manner illustrated in Figures 2 and 4. The leg 24 is longer than the leg 21 and is provided with an elongated slot indicated by the numeral 25, the material at each side of the slot 25 being thickened as indicated by the numeral 26 for the purpose of reinforcing the metal of the clamp at that region.

In forming the slot of the leg 24 of the clamp 16, said leg 24 may be slit longitudinally and the two edges of said leg 24 adjacent to said slot may be rolled through an angle of 90 degrees, having the effect of spreading the metal to provide the slot 25 at this region. If the material of the clamp 16 is approximately one-half inch wide, the material at each of the regions 26 will be approximately one-fourth inch deep. By reason of this construction, a clamp 16 may be used which is relatively narrow giving maximum clearance for insertion of the anchor 13 between the main bars 10 of a grating. Though the clamp 16 may be relatively narrow, the reinforced portions 26—26 provide adequate strength. The clamp 16 may be made of spring metal.

The bolt 15 is provided with the head 27 having a screw driver slot therein. The shank 28 of the bolt 15 has the nut 29 threaded thereon. Said nut is illustrated as being square in cross-section, this being a shape which is useful for cooperation with the elongated leg 17 of the holding member 14. The lower extremity of the shank 28 of the bolt 15 is upset as indicated by the numeral 30 whereby to prevent loss of the nut 29. It will be understood, of course, that the upsetting operation will be performed after the bolt 15 has been inserted into the aperture in the flange 20 and into the slot 25 of the clamp 16 and after the nut 29 has been threaded upon the shank 28 of said bolt.

In order that the leg 21 of the clamp 16 may underlie a main bar 10 approximately symmetrically therewith, the corner of the leg 21 above the slot 25 may be notched out as indicated by the numeral 31. This will allow said leg 21 to clear

the leg portion 17 of the holding member 14.

After the grating (which includes the main bars 10 and cross bars 11) has been located upon the horizontal flange 12a of the angle member 12, said grating may be anchored in place by applying the anchor 13 thereto from above said grating. The bolt 15 will be loosened and the clamp 16 will be turned into a position wherein it is readily insertable between adjacent main bars 10—10. Due to the fact that the slot 25 is much longer than the diameter of the shank 28 of the bolt 15, the clamp 21 may be tipped into acute angular relationship with the bolt 15, so that the anchor may be inserted through a relatively small opening from above the grating. The holding member 14 will be located upon one of the main bars 10, said main bar being disposed between the legs 17 and 19, the intermediate portion 18 of the anchor resting upon the top of said main bar. The clamp 16 will be turned into the position illustrated in Figure 2 wherein the leg 24 of said clamp underlies the horizontal flange 12a of the anchor member 12. By reason of the fact that the free extremity of the leg 21 of the clamp 16 is notched out as indicated by the numeral 31, said leg 21 may occupy a position approximately symmetrical with the adjacent main bar 10, the leg 17 of the holding member 14 being disposed within said notch 31. The bolt 15 will then be turned within the nut 29 until the clamp 16 is put under sufficient tension to hold the grating securely in position on the angle member 12. The shank 28 of the bolt 15 will assume an angular position relative to the leg 17 of the holding member 14 and the nut 29 will engage said leg 17 whereby the accidental turning of said nut 29 will be prevented.

In service, different thicknesses of the horizontal flange 12a of the angle member 12 will be encountered, and for this reason it is desirable to provide a clamp 16 which will accommodate a variation of thicknesses of this horizontal flange. According to the disclosure of Figure 5, the clamp 16 has a bend of relatively large radius between the leg 21 and the leg 24 of said clamp. In order to facilitate the bending of the clamp 16 at the portion 23, the said portion at an intermediate region thereof may be notched as indicated by the numeral 32. By reason of the thickened portions 26, the leg 24 may be reinforced without widening the clamp 16 whereby material is conserved.

The grating anchor as illustrated and described requires a minimum of material, is adapted for application to a grating or the like even in cramped places, may be readily mounted and dismounted from above the grating and will hold the grating securely in position upon the horizontal supporting member.

Though certain preferred embodiments of the present invention have been described in detail, many modifications will occur to those skilled in the art. It is intended to cover all such modifications that fall within the scope of the appended claims.

What is claimed is:

1. In an anchor, in combination, a holding member, a clamping member, a bolt having a head and a nut for said bolt, said holding member being an elongated member bent intermediate of its length to provide two legs adapted to loop over a grating bar or the like, one of said legs having an outstanding flange, the other of said legs extending a material distance beyond said first mentioned leg, said flange having an

aperture, said clamping member being an elongated member bent intermediate of its ends to form two clamping portions, said clamping portions being disposed out of registry with each other, one of said clamping portions having an opening therein, said bolt being located in said aperture and in said opening, said nut being located on said bolt, the other of said clamping portions being adapted to underlie said grating bar, said head of said bolt and said nut being located in positions wherein they are adapted to exert pressure upon said holding member through said flange and upon said clamping member to pull them toward each other to grip said grating bar.

2. In an anchor, in combination, a holding member, a clamping member, a bolt having a head and a nut for said bolt, said holding member being an elongated member bent intermediate of its length to provide two legs adapted to loop over a grating bar or the like, one of said legs having an outstanding flange, the other of said legs extending a material distance beyond said first mentioned leg, said flange having an aperture, said clamping member being an elongated member bent intermediate of its ends to form two clamping portions, said clamping portions being disposed out of registry with each other, one of said clamping portions having an opening therein, said bolt being located in said aperture and in said opening, said nut being located on said bolt, said opening being elongated in the direction of the length of its corresponding clamping portion, the other of said clamping portions being adapted to underlie said grating bar, said head of said bolt and said nut being located in positions wherein they are adapted to exert pressure upon said holding member through said flange and upon said clamping member to pull them toward each other to grip said grating bar.

3. In an anchor, in combination, a holding member and a clamping member, a bolt having a head and a nut for said bolt, said holding member comprising an elongated member having a U-turn intermediate of its length to provide a long leg and a short leg, said short leg being provided with an apertured out-turned flange, said clamping member having a U-turn intermediate of its length to provide two clamping portions, said clamping portions being angularly disposed out of registry with each other, one of said clamping portions having an opening therein, said bolt being located in said apertured flange and in said opening, said nut being located upon said bolt, the other of said clamping portions being adapted to be positioned facing said U-turn, said head of said bolt and said nut being located in positions wherein they are adapted to exert pressure upon said holding member through said flange and upon said clamping member to pull them toward each other to grip a member located in said first-mentioned U-turn.

4. In an anchor, in combination, a holding member, a clamping member, a bolt having a head and a nut located on said bolt, said holding member being elongated and bent intermediate of its length to provide two legs adapted to loop over a grating bar or the like, one of said legs having an outstanding flange, said flange having an aperture, said flanged leg being materially shorter than the other of said legs, said clamping member having a U-turn intermediate of its length to provide two clamping portions, said clamping portions being disposed out of

5

alignment with each other, one of said clamping portions having an opening therein for receiving said bolt, said bolt extending through said aperture and through said opening in said clamping member, the other of said clamping portions being notched whereby said other clamping portion may clear said holding member, the other of said clamping portions being adapted to underlie said grating bar, said head of said bolt and said nut being located in positions wherein they are adapted to exert pressure upon said holding member through said flange and upon said clamping member to pull them toward each other to grip said grating bar.

5. In combination, a grating having main bars disposed in parallel relationship with each other, said main bars being secured together, a horizontal supporting member at the extremities of said main bars, an anchor securing said grating to said supporting member, said anchor including a holding member, a clamping member, a bolt having a head and a nut on said bolt, said holding member comprising an elongated member bent intermediate of its length into a short leg and a long leg, said legs being looped over one of said main bars, said short leg being provided with a flange at its extremity, said flange having an aperture, the other of said legs extending

10

15

20

6

downwardly a material distance below said supporting member, said clamping member being bent intermediate of its length to form two clamping portions disposed out of alignment with each other, one of said clamping portions having an opening, said bolt extending through said opening and through said aperture, the other of said clamping portions underlying said one main bar, said first mentioned clamping portion being positioned underneath said horizontal supporting member, said head of said bolt and said nut being located in positions to exert pressure upon said flange and upon said first mentioned clamping portion of said clamping member to pull them toward each other to force said main bar of said grating and said supporting member into engagement with each other.
